* cited by examiner

(75) Inventor: **Marcus Nääs, Umeå (SE)**

Primary Examiner—Ian Simmons

(73) Assignee: **Bioresonator AB, Umeå (SE)**

(74) Attorney, Agent, or Firm—Renner, Otto, Boisselle & Sklar, LLP

(**) Term: **14 Years**

(57) CLAIM

(21) Appl. No.: **29/151,238**

The ornamental design for a intra-ocular pressure measurement device, as shown and described.

(22) Filed: **Nov. 21, 2001**

DESCRIPTION

(30) Foreign Application Priority Data

May 23, 2001 (SE) 01-0929

(51) LOC (7) Cl. **24-02**

(52) U.S. Cl. **D24/150**

(58) Field of Search D24/150, 172; D10/85; 600/398, 401, 405
